UNITED STATES PATENT OFFICE.

JOHN C. CROMWELL, OF CLEVELAND, OHIO.

DRIVING MECHANISM.

1,089,693.

Specification of Letters Patent. Patented Mar. 10, 1914.

Application filed April 19, 1909. Serial No. 490,703.

To all whom it may concern:

Be it known that I, JOHN C. CROMWELL, a citizen of the United States, residing at Cleveland, in the county of Cuyahoga and 5 State of Ohio, have invented a certain new and useful Improvement in Driving Mechanism, of which the following is a full, clear, and exact description.

The present invention relates to centrifugal separators of the type especially adapted 10 for the separation of cream from the whole milk.

An object has been to arrange the parts so 15 that the power transmission shall have a flexibility which I have discovered to be valuable in connection with high speed separators.

A still further object has been to avoid 20 looseness of the driving connections and thus avoid the noise consequent upon loose connections, which noise has in many other types of machine been sufficient to cause the discontinuance of their use.

The above objects and other useful advantages 25 it will be seen are attained by that embodiment of my invention described in the following specification and illustrated in the accompanying drawings, in which;

Figure 1 is a vertical section through the 30 frame of the separator showing the separating head and its driving connections together with the bearings of the driving shafts. Fig. 2 is a similar section through the upper end of the frame but at right angles to the section shown in Fig. 1, illustrating 35 the connection of the driving handle. Fig. 3 is an enlarged sectional view showing the bearings of the driving shaft and separator spindle.

The frame of the support comprises a 40 platform A on which the separator B is supported and a web or diaphragm A' in the lower part, which web or diaphragm supports the bearings for the end of the separator spindle B' and the driving shaft C. At the upper end of the frame is secured a box or housing A² in which is held a driving wheel C' through which motion is communicated to the driving shaft, the said wheel being rotated by means of a handle C² or other suitable means. Owing to the driving connection which I have shown and which will be described below, this wheel may be placed at a convenient height for operation by hand

50 without entailing the necessity for mounting the separator head B at such a height as to

make it inconvenient for the pouring of milk into the reservoir D.

The separator spindle is parallel with the vertical driving shaft and is itself hung upon 60 anti-friction bearings at the upper end thereof, which bearings are capable of a sidewise oscillation and permit the tilting of the separator spindle after the manner of the generically similar bearing shown as supporting 65 the separator in my Patent No. 856,228 issued June 11th, 1907. The spindle is provided immediately below the head with a bearing surface B³ preferably spherical in curvature, which surface is supported on 70 balls held in a raceway capable of sidewise oscillation. In the present instance the raceway is located on the interior of a ring B⁴ having a flat surface resting upon a corresponding flat annular ledge of the platform 75 A. Some suitable means such as a surrounding spring tends to hold the ring in its central position, but permits it to oscillate laterally under the influence of the separator head when the latter is rotated.

The lower end of the spindle is centered and opposed in its lateral movement by means of a surrounding circle of balls held between two independent members E, E' forming a ball-race, one of the members, the 85 lower one E' in the present instance, being movable relative to the other and held by spring pressure in such position as to force the balls against the bearing surface of the spindle. This bearing is obviously such that 90 it tends to oppose all lateral pressure and movement of the spindle. Such movement, however, is possible, and when it takes place the movable member of the ball-race shifts so as to permit the adjustment of the balls to 95 the new axial position of the spindle. This lateral movement of the spindle and adjustment of the balls to any position of the spindle is due to the fact that the lower member E' of the ball race may yield or move 100 slightly away from the fixed member E of the ball race against the action of the spring below the member E', due to the pressure of the spindle on the balls contained within the ball race.

The two sets of bearings above described for the upper and lower ends of the spindle obviously permit the latter both to tilt and to shift laterally at each end and thus accommodate itself to those peculiar tendencies of high speed separators, which seem rarely, if ever, to remain absolutely true

upon a given axis throughout their range of speeds.

The driving shaft C is hung on ball bearings at the upper end so as to have a swinging or tilting movement thereon, and has a spiral worm C³ near the upper end where it receives motion from the driving wheel and has a large spiral gear wheel C⁴ near the lower end thereof transmitting motion 10 to a smaller spiral B² fixed on the lower end of the separator spindle B'.

The bearings for the lower end of the driving shaft are provided with an anti-friction centering bearing similar to that 15 provided for the lower end of the separator spindle. By reason of this, the spiral gear C⁴ on said driving shaft may yield to the movements of the spiral on the lower end of the separator spindle and avoid all of 20 the wear and grinding which would occur if the lower end of the driving shaft did not yield. The practical advantage of this arrangement is greater than might at first appear. Machines having ball bearings that 25 operate perfectly at first, frequently will require subsequent adjustment whenever wear takes place. It is a well known fact that the users of such machines will not make such adjustment properly even when the 30 fullest directions accompany the machine. With a construction such as I have here described it will be seen that there is no adjustment which it is necessary for the user to make, the shaft and spindle being 35 self-centering and the bearings being such as to permit a yielding of the shaft to the oscillation of the spindle, thus avoiding wear and necessity for adjustment. Such machines, therefore, need not be subject to 40 the skill or lack of skill on the part of the user but will remain in the condition in which they are sent from the factory.

A further but not altogether minor advantage of this construction is the relative 45 noiselessness of the machine in action. Frames of this sort have somewhat the effect of a sounding board and any imperfection in the grinding or fitting of the gears results in a noise which is exceedingly dis-

agreeable. With a flexible driving connection such as that shown in which the gear on the driving shaft yields and accommodates itself to the oscillations of the pinion upon the spindle, the connection is practically noiseless and the disagreeable effect referred to is obviated. 50 55

Having thus described my invention, I claim:

1. Driving mechanism comprising two parallel shafts, one adapted to drive the other, a gear wheel on each of said shafts intermeshing each with the other, and a yielding bearing for each of said shafts adjacent to the gear wheels to permit the shafts to vibrate with relation to each other; 60 substantially as described.

2. A rotatable device having a downwardly extending spindle, anti-friction bearings for said device, a yielding centering anti-friction bearing about the lower 70 end of the spindle, a driving shaft parallel with the spindle, a yielding centering anti-friction bearing at the lower end of the driving shaft, and driving connections between the shaft and spindle; substantially 75 as described.

3. A rotatable device having a downwardly extending spindle, anti-friction bearings for supporting said device, a spring-pressed ball-bearing about the lower 80 end of the spindle arranged to maintain the spindle in its central position, but permitting it to tilt and shift in a lateral direction against the pressure of said spring, a driving shaft parallel with said spindle, a 85 spring-actuated ball-bearing for the lower end of said driving shaft arranged to permit the shaft to tilt and shift in a lateral direction against the action of said spring, and a gear connection between the driving 90 shaft and the end of the spindle; substantially as described.

In testimony whereof, I hereunto affix my signature in the presence of two witnesses.

JOHN C. CROMWELL.
